UNITED STATES PATENT OFFICE.

MYRON B. GORDON, OF EAST ORANGE, NEW JERSEY.

CARBURETOR CONTROL.

Application filed July 3, 1922. Serial No. 572,734.

To all whom it may concern:

Be it known that I, MYRON B. GORDON, a citizen of the United States, and a resident of East Orange, in the county of Essex and 5 State of New Jersey, have made a new and useful Invention in Carburetor Controls, of which the following is a specification.

This invention relates to carburetor control and has for an object to produce a new 10 and improved means for controlling carburetors so as to automatically produce better economy in the operation of internal combustion engines.

A further object of my invention is to 15 provide a new and improved means for automatically adjusting the supply of fuel delivered to a motor car engine in accordance with variations in speed of the engine.

A further object of my invention is to 20 produce a new and improved carburetor control for internal combustion engines which will automatically insure a rich mixture for starting purposes and for operation while the engine is heating up.

25 A further object of my invention is to provide a new and improved automatic carburetor control which decreases the percentage of fuel in the explosive mixture as the engine heats up, and which automatically provides a relatively rich mixture for 30 operation at low speeds and for starting, irrespective of the engine being heated up.

A further object of my invention is to 35 produce a new and improved carburetor control which may be easily fitted to existing carburetors and which will automatically screw down the needle valve of the carburetor so as to give the leanest efficient fuel mixture to meet varying operating conditions of the engine which the carburetor 40 serves.

A further object of my invention is to 45 produce a new and improved device for regulating the needle valve of a carburetor in accordance with the speed of the engine with which the carburetor is connected.

These and other objects which will be 50 made apparent throughout the further description of my invention are attained by means of apparatus embodying the features herein described and illustrated in the drawings accompanying and forming a part hereof.

55 I have found by experiment that a saving of about 33% in fuel may be obtained by properly adjusting the carburetor to

meet varying speeds and temperatures, as compared to operating with a fixed carburetor adjustment which permits easy starting and operation as low speeds or before the 60 engine is properly heated, as well as operation at normal speeds and temperatures. In addition to better economy in fuel resulting from proper carburetor adjustment, I have found that the engine, under such conditions, operates better and does not get fouled with carbon so quickly.

Temperature devices have been devised for providing a rich mixture when the engine is cold, and I have found by experiment that such devices are objectionable because they do not compensate for varying engine speeds. While such a device will produce good economy, the engine will stall easily in traffic and will not pull well on 70 hills or at low speeds. Such a device aids greatly in starting the engine if cold as it holds the needle valve of the carburetor open abnormally until the engine is heating up. However, when starting with the engine hot, I have found that such a device is objectionable because it maintains the 75 mixture so lean that starting is difficult.

I have also found that a device for varying the mixture in accordance with the engine speed alone has the objectionable feature of cutting down the mixture as soon as the engine gets up to speed and before it is properly heated up. As a result the engine 80 will stall easily, if it will operate at all, until it has been operated long enough to get well heated up.

In my invention I have combined both the temperature and the speed control in a very simple manner by means of a device which may be easily attached to existing motor cars or which may, if desired, be embodied in the original construction thereof. In operation the device is entirely automatic in action and results in operation at the 90 greatest efficiency under all operating conditions, when properly installed and set. The construction is such that the first cost may be so low that the device saves more than its cost, in fuel economy, in a short 95 time.

100 In the drawings, Fig. 1 is a diagrammatic perspective view of a carburetor controlling device embodying the features of my invention and associated with an internal combustion engine of a type frequently used in 105 motor cars.

Fig. 2 is a perspective view of a part of the apparatus illustrated in Fig. 1.

Fig. 3 is a diagrammatic plan view of a part of the apparatus illustrated in Fig. 1, 5 a part of the apparatus being broken away for convenience in illustration.

Referring to Fig. 1 of the drawings, I have diagrammatically illustrated a motor car engine 5 of the four cylinder water 10 cooled type, having a fan 6 at its front end for the purpose of drawing air through the radiator, not shown, of the motor car in the usual manner. The air drawn through the radiator passes back over the engine and 15 out through openings in the hood, not shown, of the motor car, and also around the rear part of the engine and out below the car. This current of air is relatively strong and assists in cooling the engine, as is well 20 known to those skilled in the art.

As illustrated, the engine is provided with an intake manifold 7, an exhaust manifold 8, and a carburetor 9 in the usual manner. This general construction is familiar to 25 those skilled in the art and requires no further description. The carburetor illustrated is of the type having a needle valve stem 10 extending upwards outside of the carburetor, and by means of which the needle valve 30 may be turned so as to vary the proportion of air and gasoline drawn into the engine.

In the construction illustrated, the carburetor stem 10 terminates at its upper end in a flat plate 11 provided with two holes 35 12. A forked rod, extending from the dash board of the car is ordinarily provided for turning the carburetor stem 10, the two prongs of the fork resting in the holes 12. In the apparatus illustrated the forked rod 40 has been removed and replaced by an automatic carburetor control embodying the features of my invention.

As shown a sheet metal vane 13, having a lower flange 14 and an upper flange 15, is attached to the carburetor stem 10 by means of a small bolt 16 passing through the lower flange 14 and a small bracket 17. As illustrated in Fig. 2, the bracket 17 consists of a strip of sheet metal bent upward in the 50 middle in order to form a pocket in which a nut 18 (shown in Fig. 1) is held in such a manner as to prevent the nut from turning when the bolt 16 is screwed down. The outer ends of the bracket 17 are bent down so 55 as to form projections 19 which are adapted to fit in the holes 12 in the flat plate 11 of the carburetor stem 10.

As shown the vane 13 is pivotally supported at its upper end by means of a 60 bracket 20 which is illustrated as passing around the exhaust manifold 8, and as provided with a downwardly extending pin 21 passing through the upper flange 15 of the vane 13. A bolt 22 serves to clamp the 65 bracket 20 rigidly on the exhaust manifold

8. The pin 21 is shown as axially aligned with the carburetor stem 10 so that the vane 13 swings about a vertical axis with the pin and the stem as supports or guides.

In the construction illustrated the bracket 20 is provided with a laterally extending arm 23 which extends along the exhaust manifold 8 towards the front of the engine 5, and which acts as a support for a strip of thermostatic metal 24. As illustrated in Fig. 3, the thermostatic metal is made up of two strips of metal 25 and 26 having different coefficients of expansion, welded or otherwise secured together so as to be distorted by different rates of expansion of the two component metals when subjected to changes in temperature. As shown the thermostatic strip 24 is rigidly secured to the outer end of the arm 23 by means of a rivet 27. The outer end of the arm 23 is shown as bent over so that the thermostatic strip 24 is spaced away from the arm 23. The strip 24 is attached so that its free end tends to bend towards the exhaust manifold 8 as it is heated up, and vice versa.

Fig. 3 is a plan view of the upper flange 15 of the vane 13, the bracket 20 being broken away so as to more clearly show the construction of the upper flange 15. As illustrated the flange 15 is provided at its inner end with a series of steps or notches 29, each slightly further away from the pin 21 in a radial direction, the highest step being nearest the body of the vane 13.

In adjusting the apparatus illustrated, the thermostatic strip 24 is bent until its free end engages the first of the steps 29 with the strip cold. It is therefore evident that the strip prevents the vane 13 from swinging backward until the strip is heated up sufficiently to cause the free end to clear the first of the steps 29. The vane may then swing backwards until the free end of the strip catches on the second and next higher of the steps 29. As the strip 24 is further deflected by increasing temperatures, the vane is released to swing backwards step by step as the free end of the strip successively clears the steps.

As illustrated a stop 30 is provided to limit the extreme backward swing of the vane 13. This stop is shown as being sufficiently long to engage the bracket 20 when the vane is deflected backwards to the fullest extent.

A small spring 31 is shown as wrapped around the pin 21, and secured at one end to the bracket 20 and at the other end to the upper flange 15 of the vane 13. This spring tends to hold the vane in its foremost position, as shown in Fig. 3. A dotted line 32 indicates the extreme backward position of the vane 13.

The operation of the device illustrated is as follows: With the engine 4 cold, the

free end of the strip 24 is engaged with the first and lowest step 27 on the flange 15 and consequently the vane 13 is locked in its foremost position. The adjustment between 5 the vane 13 and the carburetor stem 10 is such that the needle valve is opened sufficiently to produce a relatively rich mixture of air and gasoline.

The rich mixture enables the engine to be 10 easily started. As the engine speeds up the blast of air from the fan 6 impinges on the vane 13 and tends to swing it backward, and to thereby screw down the carburetor stem 10. The screwing down of 15 the carburetor stem would result in a leaner mixture but it is desirable to maintain the rich mixture until the engine becomes partially heated up. This is accomplished by reason of the thermostatic strip 24 which is 20 engaged with the first of the steps 29.

As the engine 5, and hence the exhaust manifold 8, becomes heated up, the heat is transmitted to the strip 24 which gradually bends towards the exhaust manifold and 25 eventually permits the vane 13 to swing backwards until the second of the steps 29 is engaged. It is therefore evident that with the speed of the engine maintained, the vane will be successively released as the 30 free end of the thermostatic strip 24 clears the successive steps 29, due to the force of the air blast on the vane 13 and the bending of the strip 24 in response to the increasing temperature of the engine.

35 The apparatus illustrated is preferably so proportioned that the vane 13 is deflected to its rearmost position when the engine is operating at high speed and is well heated up. When the vane is in this 40 position the carburetor stem 10 is turned sufficiently to provide the leanest efficient mixture for the engine.

As the engine slows down a richer mixture is required in order to insure proper 45 functioning of the engine. The reduced speed of the engine results in a similar reduction in the force of the blast of air from the fan 6. As a result the force of the spring 31 is sufficient to partially overcome 50 the force of the blast on the vane so that the vane is swung forward to an intermediate position. This results in a richer mixture and therefore in perfect functioning of the engine.

55 When the engine is stopped the spring 31 returns the vane to its foremost position so as to produce the richest mixture when the engine is again started. If the engine is started while still hot, the thermostatic strip 60 24 is not effective in checking the backward swing of the vane 13 and therefore the mixture is cut down as soon as the engine speeds up. This action is desirable because of the heat of the engine, which operates better and more efficiently with a

leaner mixture when starting hot as compared with starting cold. If the engine is only partially cooled off the strip 24 is partially effective in checking the backward swing of the vane. If properly adjusted the device will therefore automatically adjust the carburetor to meet different starting conditions.

When climbing hills the load on the engine increases and a richer mixture is desirable as soon as the engine begins to slow down under the increased load. This is accomplished by reason of the reduced air blast which permits the spring 31 to swing the vane forward and to thereby increase the proportion of fuel in the mixture. If the engine is shifted into a lower gear ratio the engine torque is reduced, its speed is increased and therefore a leaner mixture can be used. As the air blast from 75 the fan 6 is more effective than the air blast due to the movement of the car, the increased speed of the engine results in a leaner mixture by reason of the greater force of the air blast from the fan 6.

It is therefore evident that the mixture is varied in accordance with the speed of the engine, without requiring any attention from the operator of the car, and that this control is modified in accordance with the 80 temperature of the engine when starting or operating with the engine cold.

The adjustment of the device illustrated may be varied to meet extreme winter and summer operating conditions by varying the 100 torque of the spring 31, by bending the thermostatic strip 24, and by loosening the bolt 16 and changing the relative position of the vane 13 and the carburetor stem 10. The extreme backward position of the vane 105 30 may also be altered by bending the stop

The apparatus described does not interfere with the use of a choke valve, not shown, by means of which the mixture is 110 made extremely rich for starting purposes during very cold weather. However as the device maintains a rich mixture until the engine is heated up, it is evident that the choke does not have to be used after the 115 engine starts to operate under its own power.

It is evident that the construction illustrated is of such a nature as to be easily constructed at comparatively low cost, and that it is easily adaptable to existing motor cars of the type having a carburetor with a protruding needle valve stem. Furthermore it is evident that because of the operation of the engine at all times on the leanest efficient mixture, consistent with speed 120 and temperature, that the saving in fuel alone is sufficient to offset the cost of the device in a short time.

While I have described and illustrated 125 but one embodiment of my invention, it will 130

be apparent to those skilled in the art that various changes, modifications, additions and omissions may be made in the apparatus illustrated without departing from the spirit and scope of the invention as set forth by the appended claims.

What I claim is:

1. In combination with an internal combustion engine having a fan for assisting in the cooling of the engine and a carburetor for delivering a mixture of fuel and air to the engine, a needle valve forming a part of said carburetor and controlling the proportion of fuel in the mixture, means responsive to the blast of air from the fan for turning the needle valve to vary the proportion of fuel in the mixture in accordance with variations in the speed of the engine, and means responsive to variations in temperature of the engine for restricting the operation of the blast responsive means in accordance with the heat of the engine.
2. In a carburetor controlling device, means responsive to the speed of the engine with which the carburetor is associated for controlling the carburetor needle valve, and means responsive to the temperature of the engine for restricting the action of the speed responsive means.
3. In combination with an internal combustion engine having a fan driven by the engine, and a carburetor for supplying a mixture of fuel and air to the engine, a vane exposed to the blast from the fan and means actuated by the vane for varying the proportion of fuel and air in the mixture going to the engine in response to variations in the blast of air from the fan, means operatively connected with said vane tending to oppose the blast of air from the fan, and a thermostatic element responsive to the heat of the engine for preventing movement of the vane in response to the blast from the fan until the engine becomes at least partially heated up.
4. In combination with an internal combustion engine, means responsive to the movement of air relative to the engine for controlling the carburetor needle valve, and means responsive to the temperature of the engine for maintaining a rich mixture of fuel and air delivered to the engine while the engine is heating up.
5. In combination with an internal combustion engine having a carburetor with a valve for controlling the richness of the fuel mixture delivered to the engine, a vane operatively connected with said valve and exposed to a blast of air moving past the engine in such a manner that the force of the blast tends to move the vane so as to cut down on the percentage of fuel in the mixture, means tending to oppose the force of the blast on the vane, means for varying the adjustment between the vane and the

valve, a series of notches or steps associated with said vane, and temperature responsive means for engaging said notches successively so as to prevent movement of the vane by the blast until various temperatures have been successively attained.

6. A carburetor controlling device comprising a vane operatively connected with a carburetor in such a manner that movement of the vane varies the mixture of fuel and air delivered by the carburetor, said vane being responsive to a blast of air, a flange on said vane having a series of notches or steps, a thermostatic element engaging said notches for preventing motion of the vane in one direction until predetermined temperatures have been reached, means for limiting the extreme movement of the vane, and means for varying the adjustment between the vane and the carburetor.

7. In combination with an internal combustion engine, a fan driven by the engine, an exhaust manifold, an intake manifold, a carburetor for delivering a mixture of fuel and air to the intake manifold, a needle valve having a protruding stem and controlling the richness of the fuel and air mixture, a vane mounted on said protruding stem and exposed to the blast of air from the fan in such a manner that the force of the blast on the vane tends to close the needle valve, a bracket attached to the exhaust manifold for supporting the upper end of the vane and having an arm extending along the exhaust manifold, a flange associated with the vane and having a series of steps, a strip of thermostatic metal secured to the arm of the bracket and having a free end engaging the steps on the flange in such a manner as to oppose the movement of the vane in the direction which tends to close the needle valve, and a spring tending to hold the vane in the position which results in the richest mixture.

8. In combination with an internal combustion engine, a source of gaseous fuel supply, means movable in response to the variations of an air blast past the engine to vary the quality of the fuel mixture delivered to the engine, and thermostatic means, responsive to variations in the temperature of the engine, for controlling the movement of said means in one direction.

9. In combination with an internal combustion engine, a source of fuel mixture supply, means responsive to variations in the intensity of a blast of air passing the engine for varying the quality of the mixture delivered to the engine, and thermostatic means responsive to temperature changes in the engine for restraining a movement of said first mentioned means tending to impoverish the mixture, but imposing no restraining effect on movements tending to enrich the mixture.

10. In combination with an internal combustion engine, a source of fuel mixture supply, means responsive to variations in the speed of the engine for varying the quality of the fuel mixture delivered to the engine, and thermostatic means responsive to temperature variations of the engine adapted to oppose a mixture impoverishing movement of said first mentioned means and to permit a step by step movement of said first mentioned means in its movement to impoverish the mixture as the temperature of the engine increases.
- In testimony whereof, I have hereunto subscribed my name this 26th day of June, 1922.

MYRON B. GORDON.
